Specification for Design.

Patented May 4, 1915.

Application filed February 24, 1915. Serial No. 10,382. Term of patent 7 years.

To all whom it may concern:

Be it known that I, JOHN H. JEWETT, a citizen of the United States, residing at Appleton, in the county of Outagamie and State of Wisconsin, have invented a new, original, and ornamental Design for a Book-Rack, of which the following is a specification.

Reference is had to the accompanying drawing, in which the single figure is a perspective view of a book rack showing my new, original and ornamental design.

Copies of this patent may be obtained for five cents each, by addressing the "Commissioner of Patents, Washington, D. C."

I claim:

The ornamental design for a book rack substantially as shown.

In testimony that I claim the foregoing as my own, I have hereto affixed my signature in the presence of two witnesses.

JOHN H. JEWETT.
